UNITED STATES PATENT OFFICE.

BERNARD H. SCOTT, OF GLENDALE, AND SAMUEL E. ROSS, OF LONG BEACH, CALIFORNIA, ASSIGNORS TO SCOTT-ROSS AND COMPANY, OF LOS ANGELES, CALIFORNIA, A CORPORATION OF DELAWARE.

QUICK-ACTION RETENTION VALVE FOR WELLS.

Application filed October 6, 1926, Serial No. 139,848. Renewed October 9, 1928.

Our invention relates to quick action retention valves for wells and has among its salient objects to provide a device which will hold the weight of the column of pumped fluid 5 while the plunger valve directly beneath is making another downward stroke, said retention valve being adapted to act quickly at the initial movement downwardly of the plunger valve and said column of fluid. This 10 retention action substantially increases the efficiency of a pump in that it allows the plunger valve to open immediately upon the commencement of the downward stroke. Without it said plunger valve would be held 15 closed until the pump plunger had moved downwardly sufficiently to compress the fluid between the plunger valve and the standing valve below to a pressure greater than the pressure exerted by the weight of the fluid column above, thereby losing a certain percentage of each stroke, and this percentage of loss is greater in direct relation to the additional depth of the wells being pumped.

Another object of our invention is to provide 25 a retention valve which can be installed with the sucker rods and pump and when once in place it can only move a very short distance, thus assuring quick action in opening and closing.

Another object of our invention is to provide in such a device a retention valve seat 30 sufficiently large to permit the passage of the pump plunger, thus making it possible to pull the rods from the well at any time it may become necessary to do so, in order to renew the pumping equipment, or for any other cause, without the necessity of disturbing the pump tubing, or removing the retention valve seat.

Our retention valve seat can also be removed 35 and replaced with a new seat in case of wear, thus making it possible to use a retention valve body for an indefinite period.

Another object of our invention is to provide 40 a device of the character referred to which requires no stuffing boxes or packing of any kind, the center rod being a sliding fit sealed with the fluid being pumped.

Other objects and advantages will be apparent 45 from the following description of one practical embodiment of our invention, taken with the accompanying sheet of drawings, in which:

Figure 1 is a vertical sectional view

through a retention valve embodying our invention;

Figure 2 is an upper end view of the retention valve body;

Figure 3 is a side elevation of the same; and

Figure 4 is a view showing a well tubing 60 with pumping mechanism therein, with our retention valve shown in connection therewith, said view being partly in section.

Referring now in detail to the drawings, Fig. 4, 5 designates the usual well tubing, 65 with a standing valve, 6, at the lower end thereof, and 7 designates a plunger valve, connected to and operated by a plunger rod, 8, said rod having a reduced portion, as 8^a, for a purpose hereinafter again referred to. 70

Our invention includes in combination, a tubular section, 9, internally threaded at its opposite ends to be connected into said well tubing, 5, as seen in Fig. 4, and provided with an inner annular shoulder, 10, to receive an 75 annular valve seat member, 11, held in place by means of an inner sleeve, 12, externally threaded at its lower end and having threaded engagement with the interior of said tubular section 9, as at 13, thus clamping said 80 valve seat member 11, in place, substantially in the manner illustrated. Said inner sleeve member 12 is increased in thickness at its upper end to provide the annular beveled shoulder, 12^a, which operates as a stop for the 85 upper movement of the valve member now to be described.

The retention valve member is designated, 14, has a smooth bore, 15, through the center 90 which fits a smooth rod section, 16, of the plunger rod, 8, said fit being a sliding fit with said retention valve member, 14. Said retention valve member 14, is reduced at its lower end to provide the annular shoulder, 17, below which the body is cut away to form 95 clearance passageways, as 18, 18, between said body portion and the inside of the member, 9, whereby when said valve member, 14, is raised to lift the annular shoulder, 17, from the valve seat member 11, fluid can move upwardly around said valve member 14, through 100 said annular valve seat member, 11, and upwardly through the inner sleeve, 12. The upper end is similarly cut away from said valve body, as at 19, 19, as will be better understood by reference to the end view there-

of in Fig. 2, the upper end of said valve body being in the upper end of said inner sleeve or member, 12. Two radially sliding dogs, 20, 20, are set in the body 14, as will be clear from Fig. 1, having elongated openings, as 21, therein, and held in place by pins, 22. The dogs act as stops for the upward movement of said body member. On the upward movement of the valve body, 14, said dogs engage the shoulder, 12^a, and prevent further upward movement of said body, but this is sufficient to unseat said valve body, 14, at its shoulder, 17, from the valve seat member 11. On the downward movement, said valve member is stopped by the valve seat. When said valve member, 14, is seated on the valve seat member, 11, the passageway down through said valve mechanism is closed, and when said valve member is lifted, as on the lift or upward stroke of the plunger rod, 8, fluid passes upwardly through said valve seat member, 11, around the lower or reduced end of said valve member, and upwardly around the round or middle portion of said valve member, 14. Thus said valve member has a short movement before the dogs, 20, 20, engage with the shoulder, 12^a, in the sleeve member, 12.

While the use and operation of the device will be understood from the foregoing description, it may be briefly restated as follows: The up stroke of the plunger rod, 5, and the plunger valve, 7, lifts a column of fluid up through said retention valve, lifting said valve member 14, as above described and allowing the fluid to pass upwardly through said retention valve mechanism. As soon as said plunger valve, 7, and said plunger rod, 5, start to move downwardly, said retention valve member, 14, seats on the valve seat member 11, thus retaining or holding the column of fluid above said valve member and reducing the weight on the plunger valve member 7, and allowing it to open on its downward stroke to pick up another quantity of fluid, in a manner well understood.

When it is desired to remove said plunger rod, 8, and said plunger valve 7, from the tubing, 5, it is pulled up until the reduced part, 8^a, comes opposite the dogs, 20, 20, whereupon said dogs are free to move inwardly into said reduced portion, 8^a, and their outer ends will then pass the shoulder, 12^a, and permit said retention valve member 14, to be withdrawn with said plunger rod and plunger valve 7, for any purpose.

To this end, the distance between the dogs, 20 and the bottom of the valve member 14, corresponds to the distance between the top of the cage of the plunger valve 7 and the groove 8^a.

Thus we have provided a simple, practical and efficient quick acting retention valve for use in combination with a well tub and pumping mechanism, and while we have shown and described one practical embodiment thereof,

we are aware that changes in details can be made without departing from the spirit of the invention, and we do not limit our invention to the details shown for descriptive purposes, except as we may be limited by the hereto appended claims.

We claim:

1. A retention valve for wells comprising in combination with a well tube, plunger rod and plunger valve, a tubular member connected into said well tube, an annular valve seat therein, a valve member having a sliding fit on a portion of said plunger rod within said tubular member and having an annular shoulder adapted to seat upon said annular valve seat to close the opening therethrough, movable means carried as a part thereof for limiting the upward movement of said valve member away from said seat whereby to permit flow through said annular valve seat, and means for releasing said movable means on said valve member whereby it can be lifted out of said tubular member with said plunger rod.

2. A retention valve for wells comprising in combination with a well tube, plunger rod and plunger valve, of a tubular member forming a part of said well tube and having an annular valve seat therein, a valve member having an annular valve shoulder adapted to seat upon said valve seat to close said valve seat, said valve member having a sliding fit upon a part of said plunger rod, means on said valve member for limiting its upward movement, a part in said tubular member to be engaged by said means, and means for rendering said limit means inoperative, whereby said valve member can be lifted with said plunger rod from said tubular member.

3. A retention valve for wells including in combination, a tubular member, an annular valve seat therein, a valve member having a valve seat shoulder adapted to seat upon said annular valve seat to close the same, a rod section having a sliding fit through said valve member and adapted to be connected to the plunger rod of a pumping mechanism, limit stops for limiting the upward movement of said valve member away from said valve seat, whereby to open passageway through said tubular member, and means for rendering said limit stops inoperative to permit said valve member to be lifted out of said tubular member with said rod section.

4. A retention valve of the character referred to including a tubular member to be connected into a well tubing, a removable annular valve seat member therein, a valve member seated thereupon and adapted to close said valve seat, a section of rod having a sliding fit through said valve member, limit stops on said valve member for limiting the movement of said valve member away from said valve seat, means within said tubular member to be engaged by said limit stops, and means whereby said limit stops can be

rendered inoperative to permit said valve member to be lifted by said rod section out of said tubular member.

5. A quick acting retention valve for wells including a tubular member, an annular valve seat member therein, a sleeve having screw engagement with said tubular member and securing said valve seat member in place, said sleeve having an inner annular shoulder, 10 a valve member in said sleeve and seated upon said valve seat member to close the same, a rod having a sliding fit through said valve member, stop dogs carried by said valve member and adapted to engage the inner annular shoulder in said sleeve to limit the movement of said valve member away from said valve seat member to open passageway through said tubular member and inner sleeve, and means for rendering said stop 15 dogs inoperative to permit said valve member to move out of said sleeve with said rod.

6. A quick acting retention valve including a tubular member to be connected into a well tube, an annular valve seat member 20 therein, a valve member seated through said valve seat member and closing the same when seated thereupon, the lower end of said valve member being cut away to permit flow of fluid upwardly through said valve seat when 25 said valve member is lifted, a rod having a sliding fit through said valve member, stop dogs carried by said valve member and adapted to limit the movement of said valve member away from the valve seat, and a reduced portion on said rod adapted to permit 30 said stop dogs to move thereinto to render them inoperative, for lifting said valve member with said rod out of said tubular member.

7. A quick acting retention valve includ- 40 ing a tubular member threaded at its oppo-

site ends to be connected into a well tubing; an annular valve seat member therein, a valve member having a smaller part extended through said valve seat member and a part forming a valve to seat upon and close said 45 annular valve seat member, a rod having a sliding fit through said valve member, radially movable stop elements carried by said valve member, and means within said tubular member to be engaged by said stop elements 50 to limit the movement of said valve member away from said valve seat, said rod having a reduced portion adapted to receive the inner ends of said stop elements when in register therewith to render them inoperative as 55 stops, whereby to permit said valve member to be removed from said tubular member with said rod.

8. In a device of the character referred to, a tubular member having an inner annular valve seat, a valve member seated thereupon and closing the same, said valve member having a portion extended through said valve seat and reduced to permit upflow through said valve seat around said valve member 60 when the latter is raised, movable stop elements carried by said valve member, means within said tubular member above said stop elements to be engaged thereby to limit the upward movement of said valve member, a 65 rod having a sliding fit through said valve member, and means on said rod adapted to render said stop elements inoperative when desired to remove said valve member with 70 said rod from said tubular member. 75
